DFS. 2283

Samuel M. Richardson of New York, N.Y.
Letters Patent No. 22,463-Dated Mar. 13, 1866.
Design for a Hinge Plate.

The schedule referred to in these Letters Patent and making part of the same.

To all whom it may concern:

Be it known that I Samuel M. Richardson of the City and State of New York have invented or produced a new and ornamental Design for the Plates of Hinges, and I do hereby declare the following description thereof to be correct reference being had to the annexed drawing in which Figure 1 is a front view and Figure 2 a side view of the hinge.

My design consists in the ornamental shape given to the plate carrying the hook or pivot of a hinge, the design of said plate being represented at a, in the accompanying drawing. b, is the ordinary hook or pivot projecting from said plate.

This ornamental plate is shaped at the ends somewhat resembling the section of an acorn, and becomes not only an ornament, but at the same time a peculiarity of shape designating the hinge plate manufactured by me.

What I claim and desire to secure by Letters Patent is the Design of the shape for the hinge plate represented.

In Witness whereof I have hereunto set my signature this sixteenth day of February A.D. 1866.

Samuel M. Richardson.

Witnesses.
